UNITED STATES PATENT OFFICE.

FREDERICK SCHMID, JR., OF PHILADELPHIA, PENNSYLVANIA.

TIME-SWITCH.

1,177,279.

Specification of Letters Patent. Patented Mar. 28, 1916.

Application filed September 3, 1915. Serial No. 48,768.

To all whom it may concern:

Be it known that I, FREDERICK SCHMID, Jr., a citizen of the United States, residing at Philadelphia, in the county of Philadelphia and State of Pennsylvania, have invented certain new and useful Improvements in Time-Switches, of which the following is a specification.

My invention relates to improvements in time switches, the object of the invention being to provide a time switch in which the switch and the mechanism controlling the same are all inclosed within a box, and are of extreme simplicity, yet most efficient in operation.

A further object is to provide a time switch having a clock work mechanism to permit the release of the switch, and provide an improved arrangement of spring for turning the clock mechanism, the spring being put under tension by a lever controlling the position of the switch.

A further object is to provide improved means for holding the switch controlling lever, and improved means for releasing the same from its held position.

A further object is to improve upon the construction illustrated in Patent No. 1,012,721 granted to me December 26, 1911.

With these and other objects in view, the invention consists in certain novel features of construction and combinations and arrangements of parts as will be more fully hereinafter described and pointed out in the claims.

In the accompanying drawings: Figure 1 is a view in front elevation illustrating my improved mechanism in set position. Fig. 2 is a sectional plan view, the section being taken on the line 2—2 of Fig. 3. Fig. 3 is a view in vertical section on the line 3—3 of Fig. 2. Fig. 4 is an enlarged fragmentary detail view illustrating my improved spring for driving the clock mechanism and the parts adjacent thereto. Fig. 5 is an enlarged fragmentary sectional detail view illustrating my improved construction of lever holding mechanism, in locking position. Fig. 6 is an enlarged fragmentary detail view illustrating the recess disk operated by the clock mechanism

and the segmental disk coöperating therewith and controlling the operation of the switch operating lever, and Fig. 7 is a detail view of the parts shown in Fig. 5 illustrating the same as passing into locking position, the parts carried by the arm 31 moving in the direction of the arrow b.

1 represents a box having a cover 2 preferably made in two sections 2^a and 2^b as shown. The lower cover section 2^b is made with a circular opening 3, in which a dial 4 is located, and covered by a transparent sheet 5 held in place by a ring 6. The dial 4 at its periphery, contains a scale which indicates minutes, although of course the scale may indicate any fraction of time desired, and while my improvements are arranged for timing the switch any fraction of an hour, it is of course to be understood that any length of time may be arranged for as desired.

On the back or inner face of the cover section 2^b, a clock mechanism 7 is secured. This clock mechanism comprises a train 75 of gearing having a drive gear 8 at one end, and an arbor 9 at its other end. On the arbor 9, a disk 10 is fixed, and this disk has a recess 11 therein for a purpose which will hereinafter appear. A fork 12 80 is secured to disk 10, and at its outer end is provided with a short shaft 13 projecting through the center of a dial 4 and carrying a pointer 14 registering with the scale on the dial.

The drive gear 8 is mounted to turn with a shaft 15 carrying a ratchet wheel 16. An oscillating lever 17 is pivotally supported on the shaft 16, and carries a spring-pressed pawl 18 which engages the ratchet wheel 90 16 and causes the drive gear to turn in a direction to operate the clock mechanism. A rod 19 is pivotally mounted to the free end of lever 17, and at its free end is made with a cross bar 20. Through openings 22 95 in the bar 20, parallel rods 21 project, and are secured at their ends to a bar 23 having a central opening 24 receiving and sliding upon the rod 19. Coiled springs 25 are located around the rods 21 between bars 20 100 and 23, and when a pull is had upon the rods 21, the springs are contracted and ex-

ert a pull on the lever 17, tending to turn the drive gear 8. The rods 21 are secured to a block 26 connected by a pin 27 with a crank arm 28 on a crank shaft 29. This 5 crank shaft 29 has mounting in an extension bearing sleeve 30 which is preferably integral with the front plate section 2^b, and extends through the plate and on its outer end is fixed to my improved switch operating lever 31.

In the upper end of the box 1, and secured to a block of insulation 32, is an ordinary electric switch 33. The switch arm 34 is engaged by springs 35, tending always 15 to throw the switch to open position, and as my invention is not limited to any particular construction of switch, it is unnecessary to describe the same in detail. The switch arm 34 is connected by a link 36 with 20 a lever 37, the latter pivotally connected to the frame 38 of a clock mechanism. The pivot 39 which connects lever 37 and link 36 also connects a link 40 with said lever 37 and link 36, and the opposite end of this 25 link 40 is pivotally connected to the crank arm 28 so that the switch arm 34 and switch operating lever 31 are compelled to operate in unison.

A pointer 41 is secured to one end of the 30 lever 31, and registers with suitable printed matter on the cover to indicate the position of the switch with relation to the electric current. To hold the lever 31 in a position to maintain the electric circuit closed, I provide an improved construction of holding mechanism for the lever which will now be described.

A rocker shaft 42 is supported in suitable bearings on the inner face of section 2^b, 40 and at one end projects through a pocket 43. In this pocket on the shaft 42, a fork 44 is secured, and this fork is engaged by a dog 45 pivotally connected to a bracket 46 on the free end of lever 31. The fork is 45 formed with a short arm 42' and a long arm 52, the latter extending outwardly into the path of the end of the dog 45 when the latter is in any of the positions it may assume. A handle 47 is secured to the free end of lever 31, and a spring-pressed finger lever 48 is pivotally secured to the bracket 46, and is positioned beside the handle 47. The dog 45 at its lower end is adapted to engage between the members of the fork 44 and at its shorter end is provided with two lugs 49 and 49' at substantially right angles to each other, both of which at different times engage a shoulder 50 on the lever 48. When the lug 49 is in engagement with said shoulder the dog is locked against movement in the direction of the arrow *a*, but the dog is free to move in the opposite direction except as opposed by a spring 51 secured to the lever 48. Upon moving the

lever 48 toward the handle 47, the lug 49 is 65 released from engagement with the shoulder 50 and the spring 51 moves the dog until the lug 49' engages said shoulder, the lug 49' thereby preventing the dog from swinging outwardly too far to engage the arm 52 70 of the fork. At this time the lug 49 engages the adjacent outer face of the lever 48 and holds the dog out beyond the end of the arm 42' so as to clear the same in passing. As the lever 31 is moved downwardly to start the device into operation, the dog passes freely the arm 42' but engages the arm 52 and cams inwardly thereon as shown in Fig. 7 until the lug 49 engages the shoulder 50. This brings the end of 80 the dog between the arms of the fork and locks it in this position, as shown in Fig. 5, and the parts will be thus held until the fork pivots sufficiently to release the dog as will be hereinafter explained. Moving the 85 lever 48 toward the handle will also release the dog as is obvious from the drawing and the above description. The dotted position, therefore, of the dog indicates the position it will assume when riding into place to be 90 automatically locked, and also indicates the position the dog will assume when the finger lever 48 is operated to manually release the lever at any time desired without waiting for the automatic mechanism. While Fig. 95 5 shows the holding position of the fork 44, it must be borne in mind that when the switch is released and the clock mechanism is being held by the cam 55, the fork 44 will be in a position considerably to the 100 right of the position shown in Fig. 5, so that its longer number will receive the end of the pawl 45 and cause the latter to pivot.

The shaft 42 is provided with a crank arm 53 connected by a rod 54 with a segmental disk 55. This disk 55 is supported on a short arbor 56, and is located at right angles to the recessed disk 10 above referred to, and swings in a circle so as to move through the disk 10 and hold the disk 10 105 against rotary movement. When in this position, the parts are locked and the clock mechanism can only operate when the segmental disk 55 is swung to a position outside of recess 11. This movement of the 110 segmental disk is brought about by the pressure of the dog 45 against the longer member 52 of fork 44, while the lever 31 is held down in position to close the switch. While the parts are thus held, the clock mechanism 115 can be set as will be hereinafter explained, and turn the disk 10 with the pointer 14 thereon so as to move the recess 11 out of register with the edge of the segmental disk 55. The disk 55 at its point of contact 120 with disk 10, is made relatively sharp, so that for convenience of description, I shall refer to the sharp end of the disk as a finger

57 which not only moves through the recess 10 but also bears against the face of the disk 10 when the parts are set, and the pressure of the springs 25 as well as the springs 35 cause this finger to exert a continual pressure on the disk 10, hence it is of importance to have the finger 57 relatively sharp so as to reduce friction to a minimum.

To set the pointer 14 and disk 10, I provide a sliding shaft 58 which projects through the plate 2^b and has a knob 59 on its outer end. A pinion 60 on shaft 58 meshes with a gear wheel 61 loosely mounted on a shaft 62 supported in the frame 38 of the clock mechanism. A circular plate 63 on shaft 58 and against pinion 60 overlaps the face of gear 61, and compels the pinion 60 and gear 61 to move inwardly together while a coiled spring 64 on shaft 62 exerts an outward pressure on the gear 61, tending to hold the same out of mesh with a pinion 65 on the arbor 9.

The movement of the lever 31, when the switch is opened, is cushioned by a spring-pressed pivoted block 66 on the plate section 2^a so as to relieve the bang and jar which would otherwise occur.

The operation is as follows: To set the mechanism, lever 31 is swung downwardly and through the medium of the crank arm 38, link 40, lever 37, and link 36, operates to press the switch arm 34 upwardly into its circuit closing position. At the same time, this movement of the crank arm 28 exerts a pull on the rods 21 to contract the springs 25, causing a pull to be had upon the lever 17 to turn the drive gear 8 and the clock mechanism as above described. Any movement of the clock mechanism is, however, prevented because the segmental disk 56 is in the recess 11 of disk 10. A downward pressure on the handle 47 of lever 31 will move the dog 45 against the member 52 of fork 44, causing the shaft 42 to turn slightly and through the medium of the crank arm 53 and rod 54, will cause segmental disk 55 to turn far enough to move the finger 57 out of the recess 11. While the parts are thus held, the operator presses the knob 59 inwardly until the gear 61 meshes with pinion 65, when he can turn the knob 59 and set the pointer 14 as desired on the dial 4. In setting the pointer, the arbor 19 and disk 10 are turned so that recess 11 is moved out of register with the end of finger 57 on segmental disk 55, and when the parts above described are released, the end of finger 57 will bear against the inner face of disk 10. Springs 25 will operate the clock mechanism, and the pointer 14 will turn on the face of the dial, and when the pointer reaches zero, recess 11 will be in register with the end of finger 57 and springs 25 and 35 will operate to throw the lever 31 up-

wardly, and the switch arm 34 downwardly, thereby opening the electric circuit. When this movement takes place, the clock mechanism is stopped against any further movement by reason of the position of the segmental disk 55 in the recess 11 of disk 10, and all pressure or strain on the clock mechanism is relieved because the springs 25 are expanded. When the lever 31 swings upwardly, the rods 21 are moved downwardly in a direction to return the lever 17 to its initial position, the pawls 18 riding over the ratchet teeth 16. It will thus be observed that at every operation of the lever 31 to close the switch, the springs 25 will be put under tension to operate the clock mechanism, and the lever 31 will be held until the proper time has elapsed, when it will be released as above described and cause the switch arm 34 to open. If, at any time, it is desired to open the switch, it is simply necessary to operate the finger lever 48 to force the dog 45 to the position shown in dotted lines in Fig. 5, when the lever can be swung upwardly and the circuit broken. When the lever is again swung downwardly, the dog will automatically lock in the fork as shown, and the clock mechanism will begin to run for the unexpired period.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In a time switch, the combination with a clock mechanism, of a switch having a spring tending to open the same, a lever constructed to move the switch, a catch holding the lever and released by the clock mechanism, and a spring operating the clock mechanism and put under tension by the lever when the latter is moved to a position to close the switch, substantially as described.

2. The combination with an electric switch, of a clock mechanism, a spring operating the clock mechanism, a lever connected to the spring and to the switch and controlling the movement of both, and a catch controlled by the clock mechanism and holding the lever in position to maintain the switch closed, substantially as described.

3. The combination with an electric switch, of a clock mechanism, a spring operating the clock mechanism, a lever connected to the spring and to the switch and controlling the movement of both, and mechanism controlled by the clock mechanism constructed to hold the lever in position to

maintain the switch closed, and said lever having means thereon permitting the release of the same from said holding mechanism, substantially as described.

5 4. The combination with an electric switch, of a spring-pressed lever controlling the position of the switch, a device holding the lever in position to maintain the switch closed, a clock mechanism controlling the 10 device, a spring driving the clock mechanism and put under tension by the movement of the lever, and a manually operated means carried by the lever and permitting the release of the lever from said holding 15 device, substantially as described.

5 5. The combination with an electric switch, of a lever controlling the movement of the switch, a shaft having a fork thereon operatively engaging the lever to hold the 20 same in position to maintain the switch closed, a spring-held dog engaging the fork and adapted to be manually operated to release the lever, and a clock mechanism controlling the position of the fork, substantially 25 as described.

6. The combination with an electric switch, of a lever controlling the movement of the switch, a shaft having a fork thereon operatively engaging the lever to hold the 30 same in position to maintain the switch closed, a spring-held dog engaging the fork and adapted to be manually operated to release the lever, a clock mechanism, a recessed disk turned by the clock mechanism, a segmental disk at right angles to the recessed disk and movable into and out of the recess in said disk, a crank arm on the said shaft, connected to the segmental disk, and a spring tending to force the segmental disk into the 35 recess when in register therewith, whereby the fork is moved to a position to release the lever, substantially as described.

7. The combination with a switch, and a spring tending to open the switch, of a lever adapted to move the switch to closed position, a device holding the lever when the switch is closed, a clock mechanism controlling the device to release the lever, an oscillating lever having ratchet and pawl engagement with the clock mechanism and operating the latter, an elastic means between the said levers put under tension by the movement of the first-mentioned lever, substantially as described.

55 8. The combination with a switch, and a spring tending to open the switch, of a lever adapted to move the switch to closed position, a device holding the lever when the switch is closed, a clock mechanism controlling the device to release the lever, an oscillating lever having ratchet and pawl engagement with the clock mechanism and operating the latter, a rod connected to the ratchet lever and having a cross bar at its

free end with openings therein, parallel rods 65 operatively connected to the first-mentioned lever projected through said openings and having a cross bar at their free ends movable on the first-mentioned rod, and coiled springs on the last-mentioned rods between 70 said bars, substantially as described.

9. The combination with an electric switch, of a pivoted lever controlling the movement of the switch, a holding device holding the lever in position to maintain the 75 switch closed, a clock mechanism controlling the operation of the holding device, a spring driving the clock mechanism and put under tension by the lever in its movement to close the switch, a dial, and a 80 pointer operated by the clock mechanism and registering with the dial, substantially as described.

10. In a time switch, the combination with a switch, a spring tending to open the 85 switch, and a lever adapted to move the switch to closed position, of a device holding the lever in position to maintain the switch closed, a clock mechanism controlling the release of the lever, an oscillating 90 lever having ratchet and pawl engagement with the clock mechanism and operating the latter, elastic means between the said levers put under tension by the movement of the first-mentioned lever, and means for setting 95 the clock mechanism, said means operable only when the lever holding device is in one extreme position, substantially as described.

11. In a time switch, the combination with a switch, a spring tending to open the 10 switch, and a lever adapted to move the switch to closed position, of a device holding the lever in position to maintain the switch closed, a clock mechanism controlling the release of the lever, an oscillating lever 10 having ratchet and pawl engagement with the clock mechanism and operating the latter, a rod connected to the ratchet lever and having a cross bar at its free end with openings therein, parallel rods operatively connected to the first-mentioned lever projected through said openings and having a cross bar at their free ends movable on the first-mentioned rod, coiled springs on the last-mentioned rods between 11 said bars, and means for setting the clock mechanism, said means operable only when the lever holding device is in one extreme position, substantially as described.

12. The combination with an electric 12 switch, of a pivoted lever controlling the movement of the switch, a holding device holding the lever in position to maintain the switch closed, a clock mechanism controlling the operation of the holding device, a dial, a pointer operated by the clock mechanism and registering with the dial, a spring driving the clock mechanism, said

spring put under tension by the movement of the lever to close the switch, and means for setting the clock mechanism, said means operable only when the lever holding device is in one extreme position, substantially as described.

5 In testimony whereof I have signed my

name to this specification in the presence of two subscribing witnesses.
